UNITED STATES PATENT OFFICE.

WILLIAM E. BEE AND WILLIAM E. SIMPSON, OF DETROIT, MICHIGAN, ASSIGNEES TO
PALMER-BEE COMPANY, OF DETROIT, MICHIGAN, A CORPORATION OF MICHIGAN.

TROLLEY.

Application filed February 28, 1921. Serial No. 448,472.

To all whom it may concern:

Be it known that we, WILLIAM E. BEE and WILLIAM E. SIMPSON, a citizen of the United States of America and a subject 5 of the King of Great Britain and Ireland, respectively, residing at Detroit, in the county of Wayne and State of Michigan, have invented certain new and useful Improvements in Trolleys, of which the following is a specification, reference being had 10 therein to the accompanying drawings.

The invention relates to trolleys and has for one of its objects the provision of a trolley having a frame which may be formed of 15 material such as cast or malleable iron, and which is reinforced to carry the loads to which it is subjected, whereby the cost of manufacture is greatly decreased as compared to that of a steel frame. Another object is to provide a trolley which is adapted 20 to engage different sizes of track and has laterally adjustable frames held in their adjusted positions by cooperating serrations. A further object is the provision of means 25 upon the pin extending transversely of the frames and secured thereto for positioning the work carrying member. The invention has for other objects the novel features of 30 construction and combinations and arrangements of parts as more fully hereinafter set forth.

In the drawings:

Figure 1 is a side elevation of a trolley embodying our invention; 35 Figure 2 is an end elevation thereof, partly in section on the line 2-2 of Figure 1; Figure 3 is a top plan view thereof, partly in section on the line 3-3 of Figure 1; 40 Figure 4 is a cross section on the line 4-4 of Figure 2;

Figure 5 is a cross section on the line 5-5 of Figure 2;

Figure 6 is an end elevation of a modified construction of trolley; 45

Figure 7 is a side elevation thereof; partly in section;

Figure 8 is an end elevation of a clamping cap of the modified construction.

50 1 is the track, preferably an I-beam, upon the lower flanges 2 of which the trolley is supported. This trolley has the spaced frames 3, each of which is preferably of triangular shape and embraces the pair of 55 wheels 4 rotatably mounted upon the shafts

5 near its upper edge and at the front and rear ends thereof. Each frame comprises the front and rear plates 6 and 7 respectively, which are secured to each other by the bolts 8 and nuts 9. 60

The plates 6 have the enlarged transversely extending portions 10 at their lower edges, which have the recesses 11 for engagement by the pin 12 extending transversely of the frames. 13 are caps secured to the plates for supporting the pin from the plates. The pin 12 is rotatably mounted to permit of equalizing the load upon each of the wheels of the frames in the event that the track is not horizontal throughout its length. 70 To permit of laterally adjusting the frames 3 and to maintain the same in their laterally adjusted positions, the pin 12 has the series of recesses or cuts 16 which are engageable in by the stops 15 upon the caps 13. The stops 75 and recesses or cuts are serrations extending longitudinally of the caps and pin and those upon the pin are of a length and pitch sufficient to permit of the desired lateral adjustment of the spaced frames 3 to engage 80 tracks of different size.

For the purpose of reducing the cost of manufacture of the trolley, the frames 3 are formed of cast or malleable iron and are reinforced by members which secure the caps 85 13 to the frames. In detail, 17 are U-shaped rods which extend from the upper edges of the frames parallel to their outer faces and around the outer ends of the caps. The plates 6 have their portions intermediate 90 the arms of the rods enlarged and also the flanges 18 at their upper edges and beyond the enlargement through which the rods extend and to which they are secured by the nuts 19. 95

The load is carried from the load carrying member or clevis 20 which is mounted upon the pin 12 near its middle and passes between the enlarged portions 10 and the caps 13. In order to take care of any outward turning movement of the frames 3 relative to the pin 12, the inner ends of the caps and enlarged portions are secured to each other by the bolts 21 and nuts 22.

To position the work carrying member or 105 clevis 20, the pin 12 has the annular groove 23 at its middle which is engaged in by the clevis. This clevis is preferably formed of a round continuous bar and has its portions 24 intermediate its ends bent inwardly to be 110

separated a less distance than the diameter of the pin 12, thereby preventing upward movement of the clevis relative to the pin.

In the modified construction disclosed in Figures 6, 7 and 8, each of the frames 25 has at its lower end the integral hub 26 having at its outer end the bearing 27 for engaging the transversely extending load carrying pin 28. The U-shaped re-inforcing rod 29 passes around the hub, this bearing being preferably provided with the groove 30 for engagement by the circular portion of the U-shaped rod to prevent disengagement thereof.

For positioning the frame 25 in their various positions of adjustment to engage tracks of different size, there is the cap 31 which is secured to the inner end of the hub 26 of the frame as by means of the bolts 32, this cap having the pair of teeth 33 which are engageable in the recesses or cuts 34 extending longitudinally of the pin 28. This cap is preferably secured to the side of the hub. The teeth 33 engage the recesses or cuts 34 with sufficient clearance to permit of the desired amount of rotation of the pin 28 so that in the event the track inclines from the horizontal, equal load will be placed upon the trolley wheels carrying the frame. With this arrangement, it will be seen that the frames 25 may be adjusted to the desired positions by moving the same longitudinally upon the pin 28 after which the caps are bolted to the frames so that their teeth will engage in the recesses or cuts in the pin, thereby maintaining the frames in their adjustment positions.

From the above description it will be readily seen that we have provided a construction of trolley having a frame which can be manufactured at a greatly reduced cost and which, at the same time, will carry the loads to which it is subjected. Also a simple arrangement is provided which comprises the cooperating serrations for maintaining the frames of the trolley in their laterally adjustable spaced relations. Still another feature disclosed is the annular groove in the pin for positioning the clevis intermediate its ends to prevent its upward movement relative to the pin.

What we claim as our invention is:

1. In a trolley, the combination with a frame, of separate means for reinforcing said frame and relieving the same of direct tension stresses.
2. In a trolley, the combination with a frame for carrying a load, of a tension member for reinforcing said frame.
3. In a trolley, the combination with a frame having a bearing, of a member mounted in said bearing, and a rod upon said frame and engaging said bearing, constituting a reinforcement therefor.

4. In a trolley, the combination with a frame having a bearing, of a member for carrying the load mounted in said bearing, and a U-shaped rod upon said frame and passing around said bearing, said rod constituting a reinforcement for said frame.

5. In a trolley, the combination with a frame having a bearing at its lower edge, of wheels near the upper edge and at the front and rear ends of said frame for carrying the same, a pin engaging in said bearing for carrying the load, and a rod depending from the upper edge of said frame and passing around said bearing, said rod constituting a reinforcement for said frame.

6. In a trolley, the combination with a frame, of a cap secured to said frame, and a U-shaped rod upon said frame and passing around said cap, said rod constituting a reinforcement for said frame.

7. In a trolley, the combination with a pair of adjustably spaced frames, of means for securing said frames in various positions of adjustment, said means constituting a connection between the load and said frame, and separate means for reinforcing and relieving the same of direct tension stresses.

8. In a trolley, the combination with a pair of adjustably spaced frames, of a load carrying member secured to one of said frames, and a cap secured to the other of said frames and positioning said frames and load carrying member relative to each other.

9. In a trolley, the combination with a pair of spaced frames, of a pin extending therebetween and secured to one of said frames, a cap secured to the other of said frames, serrations upon said cap, and cooperating serrations upon said pin, whereby said last mentioned frame is positioned relative to said first-mentioned frame and said pin.

10. In a trolley, the combination with a pair of spaced frames, of means near their upper edges for supporting the same, caps detachably secured to the lower edges of said frames, a pin engaging said caps, said frames being movable longitudinally of said pin, and cooperating means upon said frames, caps and pin for positioning the same in the various positions of adjustment of said frames.

11. In a trolley, the combination with a pair of spaced frames, of a pin extending transversely thereof and secured thereto, said pin having an annular groove, a depending clevis upon said pin engaging in said annular groove, and means for preventing upward movement of said clevis relative to said pin.

12. In a trolley, the combination with a pair of adjustably spaced frames, of a pin extending transversely thereof and secured thereto, said pin having an annular groove

intermediate said frames, and a depending-upon said pin and depending between said clevis upon said pin engaging in said annular groove, said clevis having inwardly bent portions engaging said pin below its axis

5 for preventing upward movement of said clevis relative to said pin.

13. In a trolley, the combination with a pair of frames, of wheels near their upper edges for supporting the same, caps secured 10 to the lower edges of said frames, said frames being laterally movable relative to their respective caps, a pin extending transversely of said frames and secured by said caps, cooperating serrations upon said caps,

15 and pin for positioning said frames in their various positions of adjustment, a clevis

20 caps, and a groove in said pin engageable in by said clevis for positioning the latter upon the former.

14. In a trolley, the combination with a frame, of a U-shaped rod upon said frame and reinforcing the same.

15. In a trolley, the combination with a frame for carrying a load, of a U-shaped 25 rod depending from the upper edge of said frame and adapted to relieve said frame of tension owing to the load.

In testimony whereof we affix our signatures.

WILLIAM E. BEE.

WILLIAM E. SIMPSON.
